US0D1101209S

(12) **United States Design Patent** (10) **Patent No.:** **US D1,101,209 S**
(45) **Date of Patent:** **** Nov. 4, 2025**

(54) **LANDSCAPING BLOCK**

(71) Applicant: **Keystone Retaining Wall Systems, LLC**, Minneapolis, MN (US)
(72) Inventor: **Robert John Lundell**, Stillwater, MN (US)
(73) Assignee: **Keystone Retaining Wall Systems, LLC**, Minneapolis, MN (US)
(**) Term: **15 Years**
(21) Appl. No.: **29/858,525**

(22) Filed: **Nov. 1, 2022**

(51) LOC (15) Cl. **25-01**
(52) U.S. Cl. USPC **D25/115**; D25/113

(58) **Field of Classification Search**
USPC D25/56, 58, 113–125, 138, 151, 163

(57) **CLAIM**

The ornamental design for a landscaping block, as shown and described.

DESCRIPTION

FIG. 1 is a first isometric view of a landscaping block according to the design.

FIG. 2 is a second isometric view of the landscaping block according to the design.

FIG. 3 is a rear side view of the landscaping block according to the design.

FIG. 4 is a front side view of the landscaping block according to the design.

FIG. 5 is a first side view of the landscaping block according to the design.

FIG. 6 is a second side view of the landscaping block according to the design.

FIG. 7 is a top plan view of the landscaping block according to the design; and,

FIG. 8 is a bottom view of the landscaping block according to the design.

The broken lines in the drawings depict portions of the landscaping block that form no part of the claimed design.

1 Claim, 6 Drawing Sheets
